UNITED STATES PATENT OFFICE.

ROBERT L. NOTMAN, OF BUFFALO, NEW YORK, ASSIGNEE TO MCKINNON DASH COMPANY, OF BUFFALO, NEW YORK.

FOLDING OR CAMP CHAIR.

1,113,573.

Specification of Letters Patent. Patented Oct. 13, 1914.

Application filed August 9, 1909. Serial No. 511,889.

To all whom it may concern:

Be it known that I, ROBERT L. NOTMAN, a citizen of the United States, residing at Buffalo, in the county of Erie and State of New York, have invented a new and useful Improvement in Folding or Camp Chairs, of which the following is a specification.

This invention relates more particularly to folding or camp chairs of that sort comprising crossed hinged legs connected by flexible material forming the seat, and a hinged back which is adapted to be folded down against the legs.

The object of the invention is to provide a strong and desirable folding chair of this sort, which is of simple and inexpensive construction, and in which the back is provided with hooks or parts adapted to embrace the legs to which it is hinged for securely retaining the back in the upright operative position and preventing it from swinging rearwardly beyond such upright position and from falling forwardly or being accidentally knocked down.

In the accompanying drawings: Figure 1 is a perspective view of a folding or camp chair embodying the invention. Fig. 2 is a bottom plan view of the chair folded. Fig. 3 is an enlarged front elevation of one of the back hinges and retaining hooks. Fig. 4 is a side elevation thereof.

Like reference characters refer to like parts in the several figures.

A and B represent the legs of the chair which are crossed and hinged together between their ends in any suitable manner, and C represents a piece of canvas or other suitable flexible material, which connects the upper ends of the legs and forms the seat of the chair. The legs may be of any usual or suitable construction, but preferably they are formed by substantially rectangular metal frames having side bars or rods connected by top and bottom cross bars or rods, and the ends of the top cross rod of the leg frame B at the rear end of the seat extend laterally beyond side rods of this frame to form hinge pintles d for the back.

The back of the chair consists of a U-shaped frame E and a piece of canvas or other suitable material e which is preferably secured at its ends to and connects the side rods of the back frame. The side rods of the back are preferably bowed laterally

outward at e' above the canvas strip e and upset to form enlargements at e'' below the strip to prevent it from slipping out of place on the side rods, and the upper portion of the frame is also shown as bent rearwardly somewhat to make the back more comfortable. The side rods of the back frame are provided above their lower extremities with eyes or perforations e³ to receive the hinge pintles d, whereby the back is hinged to the leg frame B so as to fold forwardly. The back strip could, however, be differently arranged and held in place and the back could be hinged to the legs in any other suitable way.

The lower ends of the side rods of the back frame below the hinge eyes e³ are bent inwardly, forwardly and upwardly, forming hooks F. When the back is swung upwardly and rearwardly, these hooks strike the legs B and prevent the back from swinging backwardly beyond the intended substantially upright or operative position, shown in Fig. 1. By forcibly pressing the back rearwardly to its limit the ends of the hooks are caused to spring past the side rods of the leg frame B so as to embrace or bear against these side rods with sufficient pressure to prevent the back from swinging forwardly unless force enough is applied to it to disengage the hooks from the legs B. The hinge eyes e³ can slip on the hinge pintles to allow this spring action of the hooks. The hooks thus not only brace the back and prevent it from swinging backwardly beyond the operative position, but they effectually retain it in the upright position and prevent it from falling forwardly or being accidentally knocked down. The hooks are engaged with and disengaged from the legs to hold and release the back by the act of swinging the back to and from the operative position, and they are therefore preferable to a catch or retaining device which has to be independently operated. At the same time the hooks are integral portions of the side rods of the back frame and do not add appreciably to the cost of the chair; and furthermore, the engagement of the hooks with the legs B holds the lower ends of the side rods of the back in place and obviates the necessity for a lower cross rod for the back frame.

I claim as my invention:

1. The combination of legs, a seat, and a

back, said back and one of said legs being hinged together at the rear side of the seat, fixed hooked portions on one of said hinged parts adjacent to the hinge connection which are adapted to spring into interlocking engagement with said other hinged part and grip the same with a spring tension when the back is swung into the operative position whereby the back is positively held from forward or rearward movement.

2. The combination of crossed pivoted legs, one of said legs having laterally projecting pintles at the rear of the seat, a seat connecting said legs, and a back having a frame of inverted U-shape, the side rods of which are pivoted and movable laterally on said pintles, the lower ends of said side rods of the back being bent below the hinge pintles to form hooks which are adapted to engage with said legs and grip the same with a spring tension when the back is swung into its operative position to retain the back in this position.

3. The combination of legs comprising skeleton frames, a seat connecting said legs, a back having a skeleton frame, the side bars of which are pivoted to one of said leg frames at the rear side of said seat, the lower ends of the side bars of said back frame being bent below the pivotal connections of said bars to form hooks which are adapted to move laterally and embrace the side bars of said leg frame when the back is swung to operative position, the ends of said hooks being bent to overhang said side bars of said leg frame, whereby said hooks interlock with said side bars and hold the back from both forward and rearward movement.

Witness my hand, this 6th day of August, 1909.

ROBERT L. NOTMAN.
